CLAIM

The ornamental design for a shopping cart, as shown and described.

DESCRIPTION

FIG. 1 is a perspective view of a storage bag of a shopping cart, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a cart frame with wheels of the shopping cart, shown separately for ease of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of the cart frame with the wheels of the shopping cart where a handle of the cart frame rotates in a first angle;

FIG. 18 is a perspective view of the cart frame with the wheels of the shopping cart where the handle of the cart frame rotates in a second angle;

FIG. 19 is a perspective view of the cart frame with the wheels of the shopping cart where the cart frame is in a folded state;

FIG. 20 is an exploded perspective view of the shopping cart;

FIG. 21 is a perspective view of the shopping cart, shown in use with the storage bag disposed on the cart frame with the wheels;

FIG. 22 is another perspective view thereof;

FIG. 23 is an enlarged view of portion 23 shown in FIG. 9;

FIG. 24 is an enlarged view of portion 24 shown in FIG. 10; and,

FIG. 25 is an enlarged view of portion 25 shown in FIG. 10.

(Continued)

The broken lines in the drawings depict portions of the shopping cart that form no part of the claimed design. The additional uneven broken lines in the figures are to show enlarged portions, and do not form part of the claimed design.
